SOLE-AFFIXING MACHINE

William C. Card, Jr., Winthrop, Mass., assignor
to Compo Shoe Machinery Corporation, New
York, N. Y., a corporation of Delaware

Application March 11, 1931, Serial No. 522,738

28 Claims. (Cl. 12—33)

This invention relates to presses for use in the manufacture of shoes and more particularly to that type of shoe press which is adapted for use in those presses wherein the outer sole is affixed to the lasted upper by means of an adhesive cement.

A general object of the invention is to provide a press which is simple and sturdy in construction, efficient in operation in which the shoe may be clamped with a minimum expenditure of the operator's time, and which holds the shoe securely in position under pressure.

A more particular object of the invention is to provide a shoe press having a base portion, an inflatable pad disposed in said portion, and a fixed longitudinally disposed clamping member overlying said pad, said press having simple means for accommodating shoes of various heights and lengths.

Other objects of the invention will in part be obvious and will in part appear hereinafter.

The invention accordingly comprises the features of construction, combination of elements and arrangement of parts, which will be exemplified in the construction hereinafter set forth, and the scope of the application of which will be indicated in the claims.

For a fuller understanding of the nature and objects of the invention, reference should be had to the following detailed description taken in connection with the accompanying drawings, in which:

Figure 1 is a top plan view of one embodiment of the invention.

Figure 2 is a side elevation thereof.

Figure 3 is a longitudinal section of the same embodiment, shown with the shoe in place.

Figure 4 is a section on the line 4—4 of Figure 3.

Figure 5 is a front elevation showing the valve mechanism.

Figure 6 is a side elevation of another embodiment of the invention, certain parts being broken away for convenience of illustration.

Figure 7 is a plan view of the frame portion of the press body.

Figure 8 is a vertical transverse sectional view of Figure 6, taken along the line 8—8.

Figure 9 is a detail front elevation taken along the line 9—9 of Figure 6.

This case is a continuation in part of applicant's copending application Serial No. 427,722, filed February 12, 1930.

Referring more particularly to the drawings, in the embodiment shown there is provided a

base member 10 which is generally rectangular in shape and may be conveniently made of light metal such as aluminum or the like. The base 10 is provided with a cavity 11, the bottom of which is shaped to conform in longitudinal contour substantially to a shoe last, and in which is disposed an inflatable rubber pad 12 which may, if desired, be provided with a casing 13 of leather or the like.

Extending medially across the base portion 10 from front to rear is a bow member 14 adapted to support an instep pad 15 and a bearing member 16. The instep pad 15 may comprise a mushroom shaped rubber pad having its stem 17 carried within a recess 18 in a lug 19 which projects downwardly from the bow member 14.

The bearing member 16 may take the form of a flat plate adapted to bear against the upper heel portion of the last and supported from the bow member 14 by a screw nipple 20. This construction permits the bearing member 16 to engage with lasts of varying lengths and makes it unnecessary accurately to position the lasted shoe beneath the bearing member and the instep pad.

The casing 13 has a bottom portion 22 adapted to lie along and conform to the bottom portion of the cavity 11 and a top portion 23, adapted to bear up against the underside of the shoe. The portions 22 and 23 are joined by a vertical portion 24 of a height substantially level with the sole to permit the top portion 23 to bear up above the level of the sole at its periphery so as to exert pressure against the sole even at its extreme edge. To effect this result, it is desirable that the top portion 23 be materially concaved, even when shoes of small vertical height are being constructed. This makes it possible to utilize the same clamp for shoes of different heights without the necessity of having the parts 40 mechanically adjustable since the form of casing employed makes it possible to obtain the effect of such adjustment by the flexibility of the pad itself. The inflatable pad 12 is of such shape and contour as to conform to the interior of the 45 casing.

This vertical portion 24 preferably supports the top portion 23 which constitutes the bearing surface to engage the underside of the sole at a slightly higher level at the instep portion than at 50 the other portions of the shoe, and the bearing surface 23 is also preferably somewhat wider at its center than at the ends in order that the proper pressure may be assured at all points.

A conduit 28 extending through the bottom 55

of the pad 12 and of the base 10 is held in place by a nut 29 to make an air tight joint. This conduit carries at its outer end a valve 30.

The form of the invention illustrated in Figures 6 and 7 provides a special means for adjusting the height of the instep pad and of the bearing member whereby the inflatable pad does not have to be so large or capable of such great expansion to take care of different vertical heights of lasts because these differences of vertical heights can be taken care of by the adjustment of the instep pad and the bearing member. In this form of the invention the bow member 114 is similar to the bow member 14 of the previous modification, but the instep pad 115 and the bearing member 116 are each mounted upon a vertical movable rod 120—120, which passes through an opening 121 in the bow member 114 so that the rods may be moved downwardly in position to clamp a shoe against the pad 113 prior to the inflation thereof.

In such case, the members 115 and 116 are also provided with means for releasably securing them in downward position and preferably with resilient means to raise them automatically when released. A preferred manner of accomplishing these results is shown in Figure 6 in which the horizontal member 114b is provided above each of the openings 121 with a housing 122 in the upper portion of which is seated a spring 123 which acts between a seat 124 in the housing and a head 125 on the rod member 120; the housing 122 also being provided with a longitudinal vertical slot 126 mating with a similar slot 127 in each of the rod members 120, through which slots passes a reciprocable cam bar 128.

The cam bar 128 is provided on its lower edge adjacent each slot with a cam surface 129 which is preferably stepped as shown; the steps being similar to each other so that the rod members 120 are forced downwardly to an equal extent and are held in downward position as the cam bar 128 is moved in one direction.

The cam bar 128 is also preferably provided with a handle 130 and, as will be readily understood, when the operator has placed a lasted shoe in the press, it is necessary only for the operator to pull rearwardly on the cam bar 128, whereupon the cam surfaces 129 of the bar act against the bottoms of the slots 127 of the rod members 120 to force the members downwardly against the action of the springs 123 until the members 115 and 116 contact respectively with the instep 117 of the lasted shoe and the flat portion 118 of the shoe last, as shown in dotted lines in Figure 6, whereupon the pad 13 is inflated to press the sole firmly against the lasted upper. After the pressing operation is completed, the operator merely forces the cam bar 128 forwardly, whereupon the springs 123 raise the members 115 and 116 to the position shown in full lines in Figure 6.

The elongated shape of the bearing member 16 or 116 allows shoes of varying sizes to be treated in a press constructed as above described; since the omission of a pin to enter the last pin hole 119 of the last 112 eliminates the necessity of adjusting the instep pad 115 and the bearing member 116 along the bow member 114, and construction of the bow member 114 in a rigid or fixed form eliminates the pivoted clamping and bail members heretofore usually used, whereby the time and energy of the operator is saved.

Each of the forms of the press herein described is desirably connected to a continuous conveyor by means of lugs 45 so that the press may be

carried conveniently to and from a shoe receiving station, and it will be understood that mechanism may be employed, either automatic or manual, for connecting with the valve 30 to deflate the pad when it is desired to remove the shoe and to admit air to the pad when the new shoe has been inserted in place. 5

With the form of the invention first described, different heights of shoe may be taken care of without the necessity of adjusting the instep pad or the heel pad because the top surface of the casing is such that even when the enclosed pad is well inflated, it will nevertheless extend upwardly around the shoe at the sides of the sole to maintain the adjustment of the sole firmly in contact with the lasted upper to insure the complete adhesion as the cement dries. With this form of the invention, therefore, it is necessary only to insert the lasted shoe in place, and it will be firmly engaged as soon as air is admitted 10 to the pad. 15 20

In the form of the invention of Figures 6 and 7 the handle 130 is preferably pulled out until both the instep pad and the bearing member are substantially in contact with the upper surface 25 of the lasted shoe so that the pad is not compelled to compensate for differences in the height of the last.

A press of the kind shown in Figs. 6 and 7 facilitates the insertion and removal of the shoe 30 and at the same time minimizes the amount of air needed properly to operate the pad.

From the above description the principles of operation of the novel features of the present invention may be readily apparent to one skilled in the art. It will be understood that the press constructed as herein described may be used not only for purposes of affixing soles to shoes but also for laying soles and leveling soles, and it is therefore for purposes of convenience and simplicity of illustration that the specification and drawings have been limited to a sole-affixing operation. 35 40

Since certain changes may be made in the above construction, and different embodiments of the invention could be made without departing from the scope thereof, it is intended that all matter contained in the above description or shown in the accompanying drawings shall be interpreted as illustrative and not in a limiting 50 sense.

It is also to be understood that the following claims are intended to cover all of the generic and specific features of the invention herein described, and all statements of the scope of the invention which as a matter of language might be said to fall therebetween. 55

Having described my invention, what I claim as new and desire to secure by Letters Patent, is:—

1. A press of the class described comprising in combination a base, a rigid bow member and members fixedly carried thereby for engaging respectively the heel portion and the forepart portion of a lasted shoe, said rigid member being fixedly carried by said base during a loading and 60 inflating operation, an inflatable pad adapted to conform to and engage the sole of a shoe, a casing for said inflatable pad adapted to present a concave surface to the sole of the shoe and to maintain said concavity throughout a vertical 65 motion equal to the difference between the highest and the lowest last for substantially all heights of lasts, and means for moving said sole engaging member more firmly to engage the sole. 70

2. A device of the character described includ- 75

- ing in combination a base, a rigid bow member, a bearing member and an instep pad fixedly carried by said rigid member for engaging and bearing upon the upper face of a lasted shoe, said 5 rigid member being fixedly carried by said base during a loading and inflating operation, and a flexible sole engaging sheet having its edges supported at a height substantially level with the sole, and adapted to bear upon the underface 10 of a sole, an inflatable pad and means for confining said pad beneath and by said bearing surface, and means including said pad for moving said sole engaging sheet through a vertical displacement sufficient to press it firmly against the sole and to compensate by inflation alone for substantial 15 variations in employed last sizes.
3. A device of the character described including in combination a cupped base, a rigid bow member fixedly attached to said base during a loading operation, a last contacting seat and an instep pad immovably carried by said bow member, a flexible pad, a flexible sole engaging sheet, means for confining said pad beneath and by said sheet including means for supporting said sheet 20 at a height to bear up above the level of a sole at its periphery, for all heights of last.
4. A press of the class described comprising, in combination, a base member, an inflatable pad disposed on said base member, a bow member 25 integral with the base member and disposed over said pad, said bow member being provided with a pair of vertical openings disposed toward the ends of the pad, a rod slidable in each of said openings, an instep pad on the lower end of one 30 of said rods, a bearing member on the lower end of the other of said rods, means for releasably holding said rods in position when they are moved downwardly, and resilient means for normally urging said rods upwardly; said bearing 35 member having an elongated face adapted to engage with the top of the heel seat portion of shoe lasts of varying sizes.
5. A press of the class described comprising, in combination, a base member, an inflatable pad disposed on said base member, a bow member integral with the base member and disposed over 40 said pad, said bow member being provided with a pair of vertical openings disposed toward the ends of the pad, a rod slidable in each of said 45 openings, an instep pad on the lower end of one of said rods, a bearing member on the lower end of the other of said rods, means for releasably holding said rods in position when they are moved downwardly, resilient means for normally 50 urging said rods upwardly, each of said rods having a vertical slot, and a cam bar mounted on said bow member and passing through said slots, the lower edge of said cam bar having a pair of substantially similar cam faces each cooperating with one of said rods whereby as the cam bar is moved in one direction the rods are forced downwardly and as it is moved in the other direction the resilient means raises said rods.
6. A press of the class described comprising, in combination, a base member, an inflatable pad disposed on said base member, a bow member integral with the base member and disposed over 55 said pad, said bow member being provided with a pair of vertical openings disposed toward the ends of the pad, a rod slidable in each of said 60 openings, an instep pad on the lower end of one of said rods, a bearing member on the lower end of the other of said rods, means for releasably holding said rods in position when they are moved downwardly, resilient means for normally 65 urging said rods upwardly, each of said rods having a vertical slot, and a cam bar slidably mounted on said bow member and passing through said slots, the lower edge of said cam bar having a pair of substantially similar stepped cam faces each cooperating with one of said rods whereby as the cam bar is moved in one direction the rods are forced downwardly and as it is moved in the other direction the resilient means raises said rods.
7. A press of the class described comprising, in combination, a base member, an inflatable pad disposed on said base member, a bow member integral with the base member and disposed over 70 said pad, said bow member being provided 75
- with a pair of vertical openings disposed toward the ends of the pad, a rod slidable in each of said openings, an instep pad on the lower end of one of said rods, a bearing member on the lower end of the other of said rods, means for releasably holding said rods in position when they are moved downwardly, a cam bar mounted on said bow member, and cooperative means between said cam bar and said rods for simultaneously forcing said rods downwardly.
8. A press of the class described comprising, in combination, a base member, an inflatable pad disposed on said base member, a bow member integral with the base member and disposed over said pad, said bow member being provided with a pair of vertical openings disposed toward the ends of the pad, a rod slidable in each of said 10 openings, an instep pad on the lower end of one of said rods, a bearing member on the lower end of the other of said rods, means for releasably holding said rods in position when they are moved downwardly, a vertically disposed slot in each of said rods, and a cam bar mounted on said bow member and passing through said slots, said cam bar having a stepped edge, to provide sections of varying thickness whereby as it is moved in one direction the sections cooperate with the bottom of the slots in said rods to force them downwardly.
9. A press of the class described comprising, in combination, a base member, an inflatable pad disposed on said base member, a bow member integral with the base member and disposed over said pad, said bow member being provided with a pair of vertical openings disposed toward the ends of the pad, a rod slidable in each of said 15 openings, an instep pad on the lower end of one of said rods, a bearing member on the lower end of the other of said rods, means for releasably holding said rods in position when they are moved downwardly, resilient means for normally 20 urging said rods upwardly, each of said rods having a vertical slot, and a cam bar mounted on said bow member and passing through said slots, the lower edge of said cam bar having a pair of substantially similar cam faces each cooperating with one of said rods whereby as the cam bar is moved in one direction the rods are forced 25 downwardly and as it is moved in the other direction the resilient means raises said rods.
10. A press of the class described comprising, in combination, a base member, an inflatable pad disposed on said base member, a bow member integral with the base member and disposed over said pad, said bow member being provided with a pair of vertical openings disposed toward the ends of the pad, a rod slidable in each of said 30 openings, an instep pad on the lower end of one of said rods, a bearing member on the lower end of the other of said rods, means for releasably holding said rods in position when they are moved downwardly, resilient means for normally 35 urging said rods upwardly, each of said rods having a vertical slot, and a cam bar mounted on said bow member and passing through said slots, the lower edge of said cam bar having a pair of substantially similar cam faces each cooperating with one of said rods whereby as the cam bar is moved in one direction the rods are forced 40 downwardly and as it is moved in the other direction the resilient means raises said rods.
11. A press of the class described comprising, in combination, a base member, an inflatable pad disposed on said base member, a bow member 45

integral with the base member and disposed over said pad, said bow member being provided with a pair of vertical openings disposed toward the ends of the pad, a rod slidable in each of said openings, an instep pad on the lower end of one of said rods, a bearing member on the lower end of the other of said rods, means for releasably holding said rods in position when they are moved downwardly, resilient means for normally urging said rods upwardly, each of said rods having a vertical slot, and a cam bar slidably mounted on said bow member and passing through said slots, the lower edge of said cam bar having a pair of substantially similar stepped cam faces each cooperating with one of said rods whereby as the cam bar is moved in one direction the rods are forced downwardly and as it is moved in the other direction the resilient means raises said rods; said bearing member having an elongated face adapted to engage with the top of the heel seat portion of shoe lasts of varying sizes.

12. A press of the class described comprising in combination, a base, supporting means for bearing upon the upper part of a lasted shoe, said supporting means being permanently and immovably located a fixed vertical distance above said base during a loading operation, and an inflatable bag on said base adapted to conform to and engage the sole of a shoe, having its side walls of greater height relative to the sole of the shoe opposite the instep portion than opposite the remaining portions of the shoe.

13. A press of the class described comprising in combination, a base, supporting means for bearing upon the upper part of a lasted shoe, said supporting means being immovably located a fixed vertical distance above said base during a loading operation, and an inflatable bag on said base adapted to conform to and engage the sole of a shoe, said bag including side walls and a sole engaging member said sole engaging member being of greater width, to provide a greater fulness, opposite the instep portion of the shoe than at other portions of the shoe.

14. In a shoe press the combination comprising a pad adapted to conform to and engage the sole of a shoe including an inflatable pad of elastic material and a casing of inelastic material for said inflatable pad having side walls and a sole engaging portion, said side walls being higher relative to the height of the sole of the shoe opposite the instep portion than opposite the remaining portions of the shoe, and said sole engaging portion having its greatest width between such heightened portions of the side walls.

15. In a shoe press the combination comprising a pad adapted to conform to and engage the sole of a shoe, including an inflatable pad of elastic material and a casing of inelastic material for said inflatable pad having side walls and a sole-engaging portion, said sole engaging portion of said casing being of pronouncedly greater width, to provide a greater fulness, opposite the instep portion than opposite the other portions of the shoe.

16. A press of the class described comprising in combination, an inflatable bag adapted to conform to and engage the sole of a shoe, having its side walls of greater height relative to the sole of the shoe opposite the instep portion than opposite the remaining portions of the shoe, a framework having means for supporting said pad, a bow member extending over said pad

and immovably mounted on said framework at all times, an instep member, and a last engaging member permanently fixedly carried by said bow, said last engaging member having an elongated face adapted to engage the top of the heel portions of said last whereby shoes of varying sizes may be adjusted in proper position relative to said pad without adjustment of said last engaging member.

17. A press of the class described comprising in combination an inflatable bag adapted to conform to and engage the sole of a shoe including side walls and an upper sole engaging member, said sole engaging member being of greater width, to provide a greater fulness, opposite the instep portion of the shoe than at other portions of the shoe, a framework having means for supporting said pad, a bow member extending over said pad immovably mounted on said framework at all times during operation of the press, an instep member and a last-engaging member carried by said bow, said last-engaging member having an elongated face adapted to engage the top of the heel portions of said last whereby shoes of varying sizes may be adjusted in proper position relative to said pad without adjustment of said last-engaging member.

18. A press of the class described comprising in combination an inflatable bag adapted to conform to and engage the sole of a shoe, having its side walls of greater height relative to the sole of the shoe opposite the instep portion than opposite the remaining portions of the shoe and a covering surface for engaging the sole of the shoe, which has a pronouncedly greater fulness at the instep engaging portion than at the other portions.

19. A device of the character described including in combination a cupped base, a support member fixedly attached to said base at all times, a bearing member and an instep pad fixedly carried by said support member, a flexible sole-engaging sheet, means carried by said base for supporting said sheet at a height to bear up above the level of a sole, at its periphery, a flexible pad adapted to lie beneath and bear against the underside of said sheet, and means for inflating said pad.

20. A press of the class described comprising a base member having an inflatable pressure pad, and rigid supporting means adapted to hold a lasted shoe over said pad against upward displacement thereby, said supporting means including a last engaging member having a flat under-surface adapted to bear over a sufficient area of the top of a last cone to hold the last against transverse tilting, said base member and supporting means being permanently immovably interconnected to provide a press which is substantially free of movable parts, said pad having a shoe engaging diaphragm which is sufficiently vertically expandible to care for substantial variations in employed last sizes by inflation alone.

21. A shoe press frame comprising a base member adapted to hold a pressure pad, a bow member extending over said base member, and means on said bow member for engaging and holding a lasted shoe against upward movement, said means including a last engaging member having a flat under-surface adapted to bear over a sufficient area of the top of a last cone to hold the last against transverse tilting, said base member, bow member and shoe engaging

means being permanently immovably interconnected whereby said frame is substantially free of moving parts, and a pad carried by said base member having a shoe engaging diaphragm which is sufficiently vertically expansible to care for substantial variations in employed last sizes by inflation alone.

22. A shoe press frame comprising a base member adapted to hold a pressure pad, a rigid bow member spanning said base member and immovably fixed thereto, an instep pad fixedly carried by said bow, and a last engaging member having a flat surface for engagement with the top heel portions of lasts of varied sizes, said parts being immovable with respect to each other at all times, and a pad carried by said base member having a shoe engaging diaphragm which is sufficiently vertically expansible to care for substantial variations in employed last sizes by inflation alone.

23. A press of the class described comprising a base member, supporting means carried by said base member and located a fixed vertical distance therefrom throughout successive loading operations, said supporting means including a last engaging member having an enlarged flat under-surface adapted to bear across the top of a last cone, a vertically expansible inflatable pressure bag carried by said base member, and means for inflating said bag, said vertically expansible bag and vertically fixed supporting means being arranged to clamp different lasted shoes therebetween without adjustment of said supporting means.

35. 24. A press of the class described comprising a base member, supporting means for engaging and bearing upon the upper face of a lasted shoe assembly, said supporting means being immovably located a fixed vertical distance above said base member at all times, an inflatable pressure bag carried by said base member and adapted to bear upon the under face of the sole of such lasted shoe assembly, said bag having its sole-contacting surface of sufficient fulness to enable it by inflation alone to compensate for

variations in employed last sizes, and means for inflating said bag.

25. A shoe press frame of relatively light-weight construction comprising a pad-supporting base member, and a rigid bow member extending longitudinally over said base member and carrying an instep pad and a last-contacting seat having an enlarged flat under-surface adapted to seat across the top of a last cone to prevent the last from tilting transversely, said base and bow member being in the form of an integral casting of relatively light metal such as aluminum, and an inflatable bag on said base member having a shoe engaging diaphragm which is sufficiently vertically expansible to care for substantial variations in employed last sizes by inflation alone.

26. A shoe press frame of relatively light weight construction comprising a unitary casting of light metallic material, said casting having a base member provided with a pad-receiving cavity and a rigid bow member extending over said cavity, said frame including an instep pad and a last-contacting bearing member carried by said bow member.

27. A shoe press frame of relatively light weight construction comprising a unitary casting of light metallic material; said casting having a base member provided on its upper side with a pad receiving cavity, a rigid bow member extending over said cavity, and attaching lugs on its lower side for attachment to a conveyer; said frame including an instep pad and a last-contacting bearing member carried by said bow member.

28. In a shoe press the combination comprising a pad adapted to conform to and engage the sole of a shoe, including an inflatable pad of elastic material and a casing of inelastic material for said pad, said casing including side walls or gussets and a sole engaging portion, said gussets being of greater vertical height opposite the instep or shank portion, than opposite the remaining portions of the shoe.

WILLIAM C. CARD, JR.
